UNITED STATES PATENT OFFICE

EDOUARD BELIN, OF PARIS, FRANCE

OPTICAL RECORDING DEVICE FOR TELEGRAPHIC SIGNALING

Application filed November 30, 1928, Serial No. 322,841, and in France December 22, 1927.

The object of this invention is to provide a recording device of optical nature for telegraphic signaling, of the type in which the signals, of different signs, letters or the like, 5 produce corresponding variations of current in the line.

At the receiving end, the recording operation must transform such variations in such a way that the message or other matter to 10 be transmitted becomes impressed on a sensitized receiving surface.

In my United States Patents, Numbers 1,175,685 and 1,632,163, granted March 14, 1916, and June 14, 1927, respectively, there is 15 shown and described a so-called teletype machine which is provided with certain arrangements which enable currents to be sent into the line corresponding to the characters to be transmitted.

For receiving, the patents above mentioned, disclose an optical arrangement in which the galvanometer that receives the currents of the line produces by elongations 20 of its string, the illumination of characters corresponding to the characters of the transmitter, and these illuminated characters are reflected by mirrors disposed in groups or in spiral fashion by means of stepped surfaces, from which a sensitized receiving surface records the signs along a line at regular 25 intervals.

Certain difficulties are experienced in providing for the receiving operation in that 30 machine an illumination sufficient to enable rapid recording. My present invention, which is about to be described, enables such recording to be produced.

In principle, the currents from the line 35 produce the elongation of the string of a galvanometer of the string type, and the said galvanometer produces traces on a film which unwinds in front of it. It will be apparent, therefore, that if the film is lighted across 40 its entire width, there will be a miss (corresponding to the elongation of the string of the galvanometer) in the position corresponding to the character transmitted, and this by successive lines.

The invention will be more readily under-

stood by those skilled in the art with reference to the accompanying drawing.

In said drawing:

Figure 1 is a fragmental view of a portion of film used in carrying out the invention; 55

Fig. 2 is a face view of a line of characters for use in conjunction with the film;

Fig. 3 is a diagrammatic view of an optical apparatus constructed in accordance with the invention, and adapted to be used in connection with an oscillograph or galvanometer of the type shown and described in my aforementioned prior patents; 60

Fig. 4 shows a portion of Fig. 3 on an enlarged scale. 65

A film F (Fig. 1) is prepared which is entirely black, with light-transparent spots p; and these spots have an absolutely sharp contour and very accurately located position, so that the film is thus completely analogous 70 to an opaque perforated band, the perforations being replaced by the blanks produced by the trace of the string galvanometer.

The film is then placed (see Fig. 3) in front of a line L of signs (Fig. 2) reproducing, for example, the twenty-six letters of the alphabet, to which there can be adjoined, of course, the ten digits 0, 1, 2 . . . 9. A source of light S enables the desired amount of light to be projected, since there is here no case of being limited, as in the prior constructions, by the smallness of the galvanometer mirror. A mirror M reflects this light upon the film F which permits it to pass only through the blank of the horizontal line struck thereby, thus lighting the particular sign of the sign row L which lies behind that blank. 80

It will be understood that there is need to oscillate the mirror mechanically around its axis R in such a manner as to sweep the entire width of the film; and in the case illustrated, it will therefore oscillate between two extreme positions M1 and M2 corresponding to the extreme positions RaOa¹ and R²O² of the middle ray of the reflected beam. If there is placed behind the sign row L an optical device O, here represented diagrammatically in the form of a converging lens, 85 an image L¹ of line L will be formed; but it 100

is desired to collect the rays leaving the optical device O on the surfaces c^1 , c^2 , etc., of the spirally-stepped mirror C described in detail in Patent No. 1,632,164. As shown in that patent, it is essential that all the rays falling on the surfaces of said mirror be parallel and, in those conditions, a receiving surface L2 for the adjacent impressions will be provided.

Hence, the problem to be solved is the following:

Starting with the $RaOa^1$ and $RzOz^1$ (the two extreme rays being here mentioned because it is a case of covering all the rays comprised between those two), which do not necessarily have the same inclination about the optical axis RO, it is desired to obtain parallel rays. With this object in view, there is positioned behind the optical device O a mirror m mounted to oscillate about an axis 1; the initial position of this mirror being entirely arbitrary.

Considering, now, this mirror m (Fig. 4) articulated at 1, the extreme ray $RaOa^1$ falls on the mirror at I^1 and is reflected according to the line $I^1 r^1$; the angles i^1 and i^2 formed with the perpendicular at I^1 to the mirror m being equal. Now consider the second ray ZJ and determine what position the mirror must occupy in order that the reflected ray may be parallel with the reflected ray $I^1 r^1$; or what amounts to the same thing, determine the direction of the perpendicular to the mirror. Take any point J on the ray ZJ and from this point construct a parallel to the rays $I^1 r^1$; the perpendicular to the mirror is obviously the straight line JK that bisects the angle ZJr^1 and, consequently, the position m^2 of the mirror is obtained by striking from the axis 1 a perpendicular to the straight line JK. The point of incidence I^2 is then deduced, and the reflected ray $I^2 r^2$.

It can then be assumed from the foregoing that while the mirror M is oscillating from position M^1 to position M^2 , the mirror m must oscillate from position m^1 to position m^2 , and vice versa. A suitable mechanical connection between the mirrors M and m can readily be conceived, and may comprise, for example, a lever system embodying a lever 9 connected at one end to mirror m and articulated at the other end at 2 to a rod 7, the lever itself being fulcrumed at the previously-mentioned point 1. The other end of the rod 7 is articulated at 3 to one end of a lever 6 fulcrumed between its ends at 4 and articulated at its other end at 5 to a rod 8 attached to mirror M.

Having described my invention what I claim as new and desire to secure by Letters Patent is:—

1. Apparatus for translating telegraphic code characters optically from a movable film having said code characters in the form of light transparent spots thereon, comprising

a source of light, an oscillating mirror for reflecting the rays from said source of light upon said film, a linear element located behind said film and bearing a row or line of signs, a sensitized surface for selectively recording said signs, and an optical relay between said linear element and said sensitized surface, comprising a lens device in the path of the emitted beam, and a second oscillating mirror connected with the first mentioned oscillating mirror for movement in unison.

2. Apparatus according to claim 1, in which each mirror oscillates between two definite positions, the two mirrors moving in reverse manner one with relation to the other.

In testimony whereof I hereunto affix my signature.
